ANTON LEDERER, OF VIENNA, AUSTRIA, ASSIGNOR TO WESTINGHOUSE LAMP COMPANY, A CORPORATION OF PENNSYLVANIA.

PROCESS AND APPARATUS FOR BENDING FILAMENTS.

1,419,153.

Specification of Letters Patent. Patented June 13, 1922.

Application filed December 30, 1914. Serial No. 879,761.

To all whom it may concern:

Be it known that I, ANTON LEDERER, a subject of the Emperor of Austria-Hungary, and a resident of Vienna, Austria, have invented a new and useful Improvement in Processes and Apparatus for Bending Filaments, of which the following is a specification.

My invention relates to the manufacture of 10 filaments that are bent into zigzag form, and it has special reference to the manufacture of bent filaments for incandescent electric lamps.

One object of my invention is to provide a 15 process of forming alternate bends, of predetermined length and angular extent, in a continuously-supplied filament of wire or other pliable material.

Another object of my invention is to provide 20 means for annealing the filament bent in the manner above described and thereby causing it to permanently retain its bent shape.

A further object of my invention is to provide 25 an automatically-operated machine for carrying out the process described above.

A still further object of my invention is to provide 30 a machine for bending lamp filaments in the manner described above and for thereafter placing the bent filaments in its permanent position upon the usual filament supports of incandescent electric lamps.

In the accompanying drawing, Fig. 1 is a 35 vertical sectional view, with parts shown in elevation, of a machine constructed in accordance with the principles of my invention; Fig. 2 is a plan view, partially in section, of a portion of the machine shown in Fig. 1; Fig. 3 is a horizontal sectional view 40 of a cam ring which forms a portion of my device, and Fig. 4 is a diagrammatic plan view showing a train of gearing suitable for actuating the various parts of my device.

In the manufacture of incandescent electric lamps, especially such lamps as are provided 45 with metallic filaments arranged in zigzag form, it is desirable to give the filament a preliminary bending treatment before it is placed in position upon the filament supports of the lamps, and my process and apparatus are designed to accomplish this result. According to the modification of my invention 50 shown in the drawing, the wire or other incandescent filament is given the desired

zigzag shape by forming it upon a temporary supporting frame, which is made up of supporting points or fingers that are relatively disposed in a relation similar to the relation between the supports found in completed lamps. When the filament is thus 60 mounted and formed on the temporary supporting frame, its shape is substantially that which it is finally to assume in the lamp.

The machine by which my process is carried out consists essentially of a cylinder provided 65 with a set of radially projecting pins that are relatively arranged in the manner described above, the cylinder being adapted to be intermittently rotated. During the intervals between such intermittent rotary 70 movements, a filament-carrying guide performs a half reciprocation adjacent to the pins upon the cylinder, thereby passing the filament between the pins and winding it upon the successive pins that are presented at 75 each step-by-step movement of the cylinder. One or both of the series of pins are movable both axially and radially. The axial movement is provided for the purpose of adjusting the distance between the series of pins, 80 and the radial movement of the pins is provided in order to release the filament from the pins after it has been bent. Means are also provided for applying electric current to certain of the pins which carry the bent 85 filament upon them, for the purpose of heating to incandescence the bent portions of the filament between such pins and thereby annealing them. In order to prevent oxidation of the heated incandescent body, the bending 90 operation may be carried out in an inert atmosphere, if desired. I also provide a device for holding filament supports for lamps of the usual type, together with a feeding device by means of which the bent filament may 95 be applied to the filament supports, this feeding device being synchronized with the feeding device which forms a part of the filament-bending machine.

For a better understanding of my invention, reference may now be had to Fig. 1 of the accompanying drawing, wherein is shown a bed plate 1 which supports the various parts of my apparatus and which, as shown, is secured beneath a table 2 but which may 105 be supported in any other convenient manner. Rigidly secured to the base plate 1 is a cylindrical column 3 which is surrounded by

a rotatable shell 4 provided, at its lower edge, with a flange 5 to which is secured, in any convenient manner, as by means of screws 6, a ratchet wheel 7 that is adapted to intermittently rotate the shell 4. Near the top of the rotatable shell cylinder 4 is formed a flange 8, upon which rests a ring 9 to which is secured a ring 10, of insulating material, in which is fastened, in any suitable manner, a series of outwardly extending pins 11 which are equally spaced around the periphery of the ring 10 and are preferably given a slight downward inclination.

Rigidly secured to the top of the column 3 is a cylindrical cap 15 that carries, on its upper side, a screw 16. The screw 16 is engaged by a nut 17 to which is secured a ring 18 that is received in an annular groove 19 in the neck of a bell-shaped member 20, the lower end of which is formed into a flange 21 to which is secured a ring 22 of insulating material that carries a series of contact buttons 23 of conducting material. Each of the contact buttons 23 is provided with an opening in which is disposed a pin 24, the holes in the buttons 23 being slightly inclined upwardly. The pins 24 are radially movable in these holes, and are provided, at their inner ends, with heads 25 that rest against the face of a cam ring 26 which, as shown in Fig. 3, is nearly circular in cross section, but is provided with a flattened side 27 which is disposed to the right, as seen in Fig. 1. Each of the pins 24 is surrounded by a helical compression spring 28 which presses the pin against the face of the cam ring 26 and, when the pin is opposite to the flattened portion 27 of the cam ring 26, withdraws the outer end of the pin into the button 23. By adjusting the nut 17 on the screw 16, the bell-shaped member 20 may be raised and lowered so that the distance between the series of pins 11 and the series of pins 24 may be varied according to the heights of the filament-supporting frames of various sizes of lamps.

In order to cause the bell-shaped member 20 to move in unison with the step-by-step rotation of the shell 4, I provide a series of downwardly-extending pins 30, the upper ends of which are secured to the flange 21 and extend through apertures in the rings 9 and 10 and in the flange 8. This arrangement permits the vertical adjustment of the bell-shaped member 20 without disturbing the power-transmitting connection between the members 4 and 20.

Disposed beside the shell 4 is a vertical guide member 31 in which a rack 32 is adapted to slide. The rack 32 carries adjustably at its upper end, a guide bushing 33. The rack 32 is given a vertical reciprocatory movement by any suitable mechanism, an example of which will be described hereinafter, and the guide bush-

ing is thereby caused to reciprocate in timed relation to the intermittent rotative movement of the shell 4. Mounted upon bearings in a bracket 35 that is secured to the guide 31, is a spool 36 which carries a supply of wire or other filament material. The filament 37 is passed through the guide bushing 33 and is drawn from the spool 36 by the movement imparted to the guide bushing by the rack 32.

For the purpose of annealing the filament wire after it is wound upon the pins 11 and 24, in order to make the bends permanent and also in order to neutralize the tension of the material caused by the bending, I provide means for applying electric current to successive bent portions of the filament. As best shown in Fig. 2, such means comprises a pair of brushes 38 and 39 secured in brush holders 40 and 41 and supplied with electric current from a battery 42 through conductors 43 and 44, respectively. The brushes 38 and 39 rest upon the smooth circular periphery of the insulating ring 22, and are so spaced that they simultaneously engage two of the buttons 23 which, as stated above, are made of conducting material. Current thereupon enters the button 23, pin 24 and the portion of the filament 37 carried upon such pin, and leaves the filament through the pin 24 which is received in the button 23 that is engaged by the other brush. The section of the wire between the brushes thereupon becomes heated and thereby annealed. In order to avoid oxidation of the wire while it is exposed to the current, the entire winding device may be enclosed within a bell jar 95 or other suitable casing which may be filled with nitrogen or some other inert gas through a pipe 96.

From the foregoing discussion, it will be evident that the intermittent rotation of the shell 4, together with the vertical reciprocation of the bushing 33 carrying the filament 37, will result in winding the filament in a zigzag line around the pins 11 and 24. By reason of the circular form of that portion of the cam ring 26 that is adjacent to the bushing 33, the pins 24 are pressed outward into position to receive the filament wire, while, on the opposite side, the flattened portion 27 of the cam ring 26 permits the springs 28 to withdraw the pins and thereby release the wire. The pins are again caused to protrude from the buttons 23 before they again rotate into position to receive other turns of wire. In this manner, the winding device may be continuously operated until the supply of filament wire on the spool 36 is exhausted. The bent filament wire may either be wound upon a spool or immediately passed to a feeding device which winds the bent filament upon the filament supports of lamps. Such a filament mounting device

is shown at the right of Fig. 1 and will now be described.

Rotatably mounted upon a plate 45 that rests upon the bed plate 1, is a vertical shaft 46 that carries, at its lower end, a spur gear wheel 47 and a ratchet wheel 48 and which carries, at its upper end, a support 49 provided with a suitable chuck to receive a lamp arbor 50, which may be of the usual type employed in incandescent lamps. The support 49 should also be equipped with a suitable support 51 for the hooks of the lower filament-supporting spider that is secured to the arbor 50. Rigidly secured to the plate 15 45 is a standard 55, to which is adjustably secured a bracket 56 provided at its outer end with a bearing 57 in which is slidably disposed a rod 58 provided with a knob 59 and with a pin 60 for limiting the downward movement of the rod 58. Surrounding the lower end of the rod 58 is a flanged sleeve 61, to the lower side of which is attached a spur gear wheel 62. A bracket 63 is secured to the under side of the gear wheel 25 62 and carries, at its lower end, a support 64 which is adapted to receive the upper supporting spider that is attached to the arbor 50. The supports 49 and 64 are caused to rotate intermittently in unison with each 30 other and with the intermittent movement of the shell 4 of the bending device. In order to cause them to rotate in unison with each other, I provide a pinion 65 meshing with the gear wheel 47 and an elongated pinion 66 meshing with the gear wheel 62. The pinions 65 and 66 are both secured to a vertical shaft 67, the lower end of which is received in a bearing in the plate 45 and the upper end of which is received in a bearing 40 in a bracket 68 that is carried by the standard 55.

In order to guide the bent filament to the hooks with which the filament support is provided, a vertical guide 70 is disposed near the shaft 46, and, upon this guide, a rack 71 is adapted to be reciprocated in unison with the rack 32 which forms a part of the bending device. The rack 71 carries a guide 72 provided with an opening 73 through which 50 the filament 37 is caused to pass.

The supporting devices 49, 51 and 59 to 64 may be variously modified as convenience may require, the result to be attained by these supporting members being to hold in 55 position the exceedingly fine hooks of the filament-supporting frame while mounting the filament, in order to prevent the hooks from being bent out of shape. The supports must, of course, be movable in order that 69 supporting frames with their hooks may be inserted in the feeding device and removed from it after the filament has been applied. In the structure shown in Fig. 1, such relative movement is effected by raising the rod 65 58 by means of the knob 59. When a new

filament support is placed in position, the support 64 is again lowered, the extent of such downward movement being limited by the pin 60. The length of the pinion 66 permits the supporting mechanism, which includes the gear wheel 62, to be raised and lowered without affecting the relative angular positions of the upper and lower supports 49 and 64 with respect to their common axis. 75

Any suitable mechanism may be employed for causing the ratchet wheel 7, which drives the shell 4, and the ratchet wheel 48, which drives the shaft 46, to rotate intermittently in unison and for causing the racks 32 and 71 to reciprocate vertically in unison and in timed relation to the step-by-step movement of the ratchet wheels 7 and 48. It is to be understood that the train of gearing shown in the drawings is merely illustrative and that numerous other power-applying devices may be readily adapted to this purpose. As shown diagrammatically and in development in Fig. 4, a driving motor 75 is provided with an armature shaft 76 carrying a worm 77 meshing with a worm wheel 78 that is secured to a vertical shaft 79. Secured to the gear wheel 78 is a wrist pin 80 which rotates in a yoke 81 secured to one end of a reciprocating rack 82 that meshes with a pinion 83 secured to a horizontal shaft 84 which carries two similar pinions 85 and 86. The pinion 85 meshes with the vertical rack 32, and the pinion 86 meshes with the vertical rack 71. The dimensions 95 of the opening of the yoke 81 are such that the wrist pin 80 will effect intermittent reciprocation of the rack 82. Since the pinions 85 and 86 are of equal size, the racks 82 and 71 will be reciprocated at equal times 100 and for equal distances, and the guides 33 and 72 will therefore feed the filament wire simultaneously and for equal distances. 105

The gear wheel 78 meshes with a smaller gear wheel 87 having one-half as many teeth 110 as the gear wheel 78. The gear wheel 87 carries a wrist pin 88 co-operating with a yoke 89 formed on a bar 90 which carries two pawls 91 and 92 of which the pawl 91 engages the teeth of the ratchet wheel 7, 115 while the pawl 92 engages the teeth of the ratchet wheel 48. Holding pawls 93 and 94 are provided to prevent reverse rotation of the ratchet wheels 7 and 48, respectively. The wrist pin 88, which co-operates with the yoke 89, effects intermittent reciprocation of the bar 90 and the pawls 91 and 92, and thereby imparts a simultaneous step-by-step movement to the ratchet wheels 7 and 48 120 and, consequently, to the shell 4 and the support 49. Since the gear wheel 87 has only one-half as many teeth as the gear wheel 78, it makes two rotations during each rotation of the gear wheel 78, and the ratchet wheels 7 and 48 are therefore operated twice 125 130

during each complete reciprocation of the racks 32 and 71 and the filament guides 33 and 72.

The steps of my process and the structural details of my apparatus may be variously modified without departing from the spirit and scope of my invention, and it is therefore to be understood that my invention is not restricted to the precise embodiment herein shown and described, but that it comprehends all such modifications as fall within the scope of the appended claims.

I claim as my invention:

1. A filament-bending machine comprising a set of forming fingers, supporting means carrying said forming fingers, means for imparting intermittent movement to the said supporting means, and a reciprocable guide member mounted for movement in a rectilinear path for applying a filament to one of the said fingers during each of the said intermittent movements of the said supporting means.

2. A filament-bending machine comprising a rotatable cylindrical member, means for imparting intermittent movement to the said member, a set of pins radially extending from the said member, and a reciprocable guide member mounted for movement in a rectilinear path for applying a filament to one of the said pins during each of the said intermittent movements of the said cylindrical member.

3. A filament-bending machine comprising a rotatable support, means for imparting intermittent rotation to the said support, two series of pins radially extending from the said support, and an intermittently reciprocating guide member arranged to move in a rectilinear path for applying a filament to the said pins during the said intermittent movements of the said cylinder.

4. A filament-bending machine comprising a rotatable cylindrical member, means for imparting intermittent rotation to the said member, two series of pins radially extending from the said member, and an intermittently reciprocable filament-guiding device adapted to reciprocate in a rectilinear path adjacent to the said cylindrical member and in a direction parallel to its axis, for winding the said filament upon the said pins.

5. A filament-bending machine comprising means for supporting a set of forming fingers, means for imparting intermittent movement to the said supporting means, and means for applying a filament to one of the said fingers during each of the said intermittent movements of the said supporting means, the said filament-applying means comprising a filament-guiding member adapted to reciprocate in a rectilinear path adjacent to the said pins during the intervals between the said intermittent movements of the said supporting means.

6. A filament-bending machine comprising means for supporting a set of forming fingers, means for imparting intermittent movement to the said supporting means, an intermittently reciprocating guiding member arranged to travel in a rectilinear path for applying a filament to one of the said fingers during each of the said intermittent movements of the said supporting means, and means for causing the said filament to be released from the said fingers.

7. A filament-bending machine comprising a rotatable cylindrical member, means for imparting intermittent movement to the said member, a set of pins radially extending from the said member, an intermittently reciprocating guide member arranged to travel in a rectilinear path for applying a filament to one of the said pins during each of the said intermittent movements of the said cylindrical members, and means for causing the said pins to successively release the said filament.

8. A filament-bending machine comprising a rotatable support, means for imparting intermittent rotation to the said support, two series of pins radially extending from the said support, an intermittently reciprocating guide member arranged to move in a rectilinear path for applying a filament to the said pins during the said intermittent movement of the said cylinder, and means for causing the said pins to successively release the said filament.

9. A filament-bending machine comprising a rotatable cylindrical support, a plurality of pins radially associated with the said support, a relatively stationary cam for causing each of the said pins to protrude from said support and for thereafter permitting it to be withdrawn into the said support, and springs for pressing the said pins into engagement with the said cam.

10. A filament-bending machine comprising a circular support, a set of pins associated with the said support and radially movable with respect thereto, and another set of pins also associated with the said support and movable with respect to the said first-named set of pins, the pins in the said last-named set being radially fixed with respect to the said support.

11. A filament-bending machine comprising a movable support, a set of pins associated with the said support and adapted to move therewith, a second support loosely associated with the said movable support, a second set of pins secured to the said second support, and means for connecting the said two supports to move in unison, the said connecting means permitting the distance between the said sets of pins to be varied.

12. A filament-bending machine comprising a rotatable support, a set of pins radially mounted in the said support and adapted to

project from its periphery, the said pins being adapted for individual radial movement with respect to the said cylindrical support, a second support loosely associated with the 5 said first-named support and carrying a second set of radially disposed and individually immovable pins, and pins secured to the said first-named support and extending through openings in the said second 10 support.

13. A filament-bending machine comprising a set of pins adapted to have a filament bent upon them and disposed in spaced members of electrical conducting material that 15 are arranged upon a movable support of non-conducting material, electric contact members adapted to engage the said movable support and so spaced apart as to simultaneously engage two of the said conducting 20 buttons, and means for energizing the said contact members.

14. A filament-bending machine comprising a rotatable support carrying a member of electrical insulating material having a 25 circular periphery coaxial with the axis of the said support, spaced buttons of electrical conducting material disposed in the said insulating member and carrying outwardly projecting pins, the outer surfaces 30 of the said buttons being substantially even with the periphery of the said insulating member, a pair of electric contact brushes adapted to engage the periphery of the said insulating member and so spaced apart as 35 to simultaneously engage two of the said conducting buttons, and means for energizing the said brushes.

15. A filament-forming machine comprising means for forming bends in a continuous 40 filament, and means operating synchronously with the said bending means, for simultaneously mounting bent portions of the same filament upon filament supports for incandescent lamps.

45 16. A filament-forming machine comprising means for forming bends in a continuous filament, and means operating synchronously with the said bending means, for simultaneously mounting bent portions of 50 the same filament upon filament supports for incandescent lamps, the said bending means and the said mounting means each comprising an intermittently rotatable support, a filament guide adapted to reciprocate adjacent to the said support and in timed relation thereto, and means for intermittently rotating the said supports in unison and for reciprocating the said guides in unison.

60 17. A process of forming a filament for an incandescent lamp that comprises forming zigzag bends in a length of filament material, applying electric current to successively bent sections of the said filament to anneal it and to cause it to retain its 65 bent form, and mounting the said bent and

annealed filament upon a filament support for an incandescent lamp.

18. A process of forming a filament for an incandescent lamp that comprises forming zigzag bends at predetermined intervals 70 in a length of filament wire, applying electric current to bent sections of the said filament in succession, and mounting the said filament upon a filament support for an incandescent lamp. 75

19. A process of forming a filament for an incandescent lamp that comprises forming zigzag bends at predetermined intervals in a length of filament wire, and applying electric current to bent sections of said filament 80 in succession.

20. The method of shaping straight tungsten wire of great length into sinuous zigzag form by a continuous operation consisting in feeding the wire through a shaping device 85 which bends the wire passing through it into a zigzag form with uniformly recurring bends, heating each convolution while in the shaping device to set it, and releasing a shaped convolution from said device for 90 each new convolution formed from the straight wire.

21. The method of shaping straight tungsten wire of great length into sinuous zigzag filaments by a continuous operation consisting of feeding the wire through a shaping device which bends the wire passing through it into a zigzag form consisting of convolutions with uniformly recurring bends and holds a plurality of convolutions side by side 95 after forming them, heating the straight portions of each convolution to incandescence in succession and while the convolution is still held in said device, and releasing the shaped convolution from said device for each 100 new convolution formed from the straight wire.

22. A filament forming machine comprising a shaper constructed to impart a zigzag form to a wire stretched on it, a wire guide 110 for stretching a wire on said shaper, driving means for producing relative movement of said shaper and said guide to stretch a wire on said shaper in zigzag form, and means controlled by said driving mechanism for 115 heating and setting the wire while it is stretched on said shaper.

23. A filament forming machine comprising a shaper constructed to impart a zigzag form to a wire and mounted to travel, a wire 120 guide movable transversely to the line of travel of said shaper, driving mechanism for actuating said shaper and said guide in definite relation to each other to stretch a wire on the shaper in zigzag form, and means for 125 heating each loop of the zigzag wire in succession and thereby setting the wire permanently while said wire is stretched on said shaper.

24. A filament forming machine compris- 130

ing a rotatable shaper provided on its rim with radial projections arranged in two circumferential rows, a wire guide mounted to move across the rim of said shaper and to pass through both rows of projections, driving mechanism for rotating said shaper and moving said wire guide to and fro to bend a wire around a projection in one row and then in the other alternately and thereby stretch the wire on said shaper in a zigzag form, and means controlled by said driving mechanism for passing current through each loop of the zigzag in succession while the wire is stretched on the shaper to give said wire a permanent set.

25. A filament forming machine comprising a traveling shaper having a plurality of pins on its surface, a wire guide to move

back and forth across the surface of said shaper, driving means for moving said shaper and said guide relatively to each other to stretch the wire from said guide on said pins in a zigzag form, means encountered by said pins at a point in their travel beyond said guide for causing current to flow through each loop of the wire in succession as it passes a predetermined point, and means cooperating with said shaper at a subsequent point, in its travel for automatically stripping said formed filament from the pins.

In testimony whereof, I have hereunto subscribed my name this nineteenth day of Dec. 1917.

ANTON LEDERER.
